UNITED STATES PATENT OFFICE.

HOWARD GOULD NORTHRUP, OF CHICAGO, ILLINOIS.

DESIGN FOR A FAUCET-CUSHION.

SPECIFICATION forming part of Design No. 33,464, dated October 30, 1900.

Application filed March 22, 1900. Serial No. 9,809. Term of patent 14 years.

To all whom it may concern:

Be it known that I, HOWARD GOULD NORTHRUP, residing at Chicago, in the county of Cook and State of Illinois, have invented and 5 produced a new and original Design for Faucet-Cushions, of which the following is a specification, reference being had to the accompanying drawings, wherein—

Figure 1 is a side elevation of a faucet-cushion embodying my design. Fig. 2 is an axial section of the same, and Fig. 3 a bottom plan view thereof.

The characteristic features of my design comprise a hollow cylindric body or shank 5 portion 1, provided at its lower end with a relatively large or prominent rounded bead or projection 2, one of the side margins of which is coincident with the end margin of

the cushion as a whole, the size of the head being such as to cause the body to appear as 20 projecting from a somewhat-flattened sphere at one of the flattened sides thereof. The longitudinal bore or hollow 3 of the cushion is circular and of uniform diameter throughout its principal length, as best shown in Fig. 25 2, but is provided at its lower end within that portion encircled by the bead 2 with an annular enlargement or rabbet 4.

I claim—

The design for a faucet-cushion, substantially as herein shown and described.

HOWARD GOULD NORTHRUP.
